MAILBOX SUPPORT

Carl R. Taylor, 5210 S. Wheeling, Tulsa, Okla.

Filed Nov. 12, 1963, Ser. No. 77,340

Term of patent 14 years

(Cl. D74—9)

My design for a mailbox support is characterized by the particular ornamental arrangement of the post in association with the name plate and address plate of the owner of the mailbox, all as shown in solid lines in the drawings.

The broken lines shown in the several views are disclosed for illustrative purposes only.

I claim:

The ornamental design for a mailbox support, as shown and described.
